ELECTRICAL HEATING DEVICE

Lawrence F. Black, United States Army, and
Clarence H. Mellor, United States Army, Denver, Colo.

Application September 25, 1942, Serial No. 459,617

13 Claims. (Cl. 219—13)

(Granted under the act of March 3, 1883, as
amended April 30, 1928; 370 O. G. 757)

The invention described herein may be manufactured and used by or for the Government for governmental purposes, without payment to us of any royalty thereon.

This invention relates to an apparatus for heating by electricity and more particularly to an electrical induction heater for small metal parts such as soldering irons and the like.

While devices for heating small metal parts such as soldering irons, rivets, etc., are well known in the patented art, such devices generally require either a flame source of heat or, if electrical, generally require the use of a heat-radiating element employing a comparatively high resistance conductor. Either of these two modes of heating, i. e., flame source or electrical resistance element, is comparatively expensive to operate if kept hot all of the time, and, alternatively, if they are allowed to cool and then are restarted each time that a particular article is to be heated, they necessarily take a certain amount of time to reach an operating temperature. By our device, we eliminate the need for a flame source of heat and, at the same time, utilize electricity as the heating medium without employing an electrical resistance unit to supply the heat externally to the object being heated. Furthermore, although our device stands ready for operation whenever the primary circuit is energized, it draws a substantial electric current only when the part to be heated is inserted into the secondary circuit. Another advantage is the elimination of switches since the insertion of the part to be heated brings our device into operation and its withdrawal causes the device to cease operation.

Accordingly, it is an object of the present invention to provide an apparatus for electrically heating small metal parts, such as soldering irons and the like.

Another object of the present invention is to provide an electrical heating apparatus for small metal parts such as soldering irons and the like which eliminates the necessity of using an open flame and which is fast, efficient and inexpensive in operation.

Another object of the present invention is to provide an electrical induction heater for small metal parts such as soldering irons and the like which, although connected to an electrical circuit, remains normally inoperative until the part or parts to be heated are inserted into the secondary circuit of the induction heater device.

Another object of the present invention is to provide an induction heater for small metal parts

such as soldering irons and the like which comprises a closed core transformer having a primary circuit and a closed secondary circuit so arranged that substantially no current flows in the secondary circuit until the part to be heated is inserted into said secondary circuit.

These and other objects of our invention will become apparent from the following detailed description taken in conjunction with the accompanying drawings and the invention will be pointed out with particularity in the claims appended hereto.

In the drawings:

Fig. 1 is a front view of an embodiment of our invention.

Fig. 2 is an end view of the embodiment shown in Fig. 1.

Fig. 3 is a sectional view taken on line 3—3 of Fig. 2.

Fig. 4 is a sectional view taken on line 4—4 of Fig. 1.

Fig. 5 is a perspective view of a soldering iron adapted for use with our invention.

Fig. 6 is a perspective view of a solder ladie suitable for use with our invention.

Fig. 7 is a perspective view of the embodiment of our invention disclosed in Fig. 1 with a soldering iron mounted in heating position.

Fig. 8 is an end view of another embodiment of our invention.

Fig. 9 is a sectional view taken on line 9—9 of Fig. 8.

Fig. 10 is an end view of another embodiment of our invention.

Fig. 11 is an end view of a modification of the embodiment of our invention disclosed in Fig. 8.

Fig. 12 is an end view of a modification of the embodiment of our invention disclosed in Fig. 10.

Figs. 13 and 14 are diagrammatic drawings showing certain electrical characteristics of our invention.

Referring to the drawings, Figs. 1 to 4 and 7 illustrate a preferred embodiment of our invention in which a primary coil 10, having a pair of electrical lead wires 11 which are connected to a suitable source of electric power, not shown, is mounted to surround a portion of the periphery of a closed core 12 made of laminated magnetic metal such as silicon steel stampings or similar suitable material. Core 12 is formed from a series of interleaved right-angled shaped stampings 13 and 14 which act, in a manner well known in the art, to reduce eddy current loss. Surrounding core 12 is a secondary winding 15 which is preferably made in the form of a con-

tinuous loop of metal having good electrical conductivity such as copper or aluminum and which is mounted so that it entirely surrounds core 12. As will be seen from the drawings, secondary 15 is formed in modified ellipse shape so that the long sides are substantially straight and the short connecting ends are curved, thereby giving the appearance of a race track. We define this figure as mixtilinear and hereinafter when the word mixtilinear figure is used we intend it to mean a figure resembling an ordinary race track in general appearance. The secondary 15 has in each parallel straight side of the mixtilinear loop member a plurality of aligned openings 16 adapted to receive the part or parts to be heated.

Referring to Fig. 3, primary coil 10 is composed of a plurality of conductors 23 surrounded by glass insulation 24 although other suitable insulating material may be used if desirable. The secondary member 15 is preferably formed of a copper or aluminum bus-bar cast or forged, or otherwise formed, into the shape illustrated in Fig. 7. The openings 16 in the secondary member 15 are of circular orifice shape and are adapted to receive a cylindrical metal member of substantially the same configuration and diameter as that of the individual orifices 16. The secondary member 15 is preferably mounted adjacent leg 12d of the transformer core 12 opposite leg 12a upon which the primary coil 10 is mounted. In this position secondary 15 surrounds, in a single loop of mixtilinear form, the two legs 12b and 12c of the transformer core 12 which are substantially at right angles to the leg 12a upon which the primary coil is mounted. Also, the axis of the secondary 15 is substantially at right angles to the axis of the primary coil 10. While the manner of supporting the secondary winding 15 is not shown, it will be understood that it is supported to surround core 12 by means which insulate it from said core.

A soldering iron and a solder ladle suitable for use with our invention are disclosed in Figs. 5 and 6. Referring to Fig. 5, the soldering iron comprises a head 17, preferably made of copper although other electrical conducting materials may be used, a wire 18 and a handle 19, the latter being made of wood or some other suitable heat insulating material. Referring to Fig. 6, the solder ladle comprises a ladle cup 20, preferably made of copper or similar suitable electrical conducting material, a stem 21 and a handle 22.

Referring to Fig. 7, it will be seen that the mixtilinear secondary 15 is disclosed as having a part to be heated, in this case a soldering iron of the type disclosed in Fig. 5, thrust into a pair of the openings 16 so that member 17 constitutes a bridge between the straight parallel sides of secondary 15 and forms two complete electrical circuits surrounding legs 12b and 12c of core 12. The actual bridging by member 17 is more clearly shown in the dotted line portion of Fig. 4. Member 17 is so formed that it fits into opening 16 securely and forms a good electrical contact, yet it can be withdrawn quickly. The manner in which member 17 is heated is explained hereafter.

Figs. 8 and 9 disclose another embodiment of our invention in which the transformer secondary is modified in shape, although still retaining its general mixtilinear appearance, to permit the insertion of a part to be heated without extending the part into the space surrounded by the magnetic core. Referring to Fig. 8, there is dis-

closed a primary coil 10, mounted on a laminated magnetic core 12, and a secondary winding 25. Secondary 25 is formed from a bar of material having a high electrical conductivity such as copper or aluminum, said bar being provided at the center portion thereof with a protuberance 26, of the same width as the bar, having a curved face 26a formed therein. The ends of the bar are then bent around as shown at 29 to form a loop surrounding the magnetic core 12 and extending through the air space surrounded by core 12 to form an opening 27, bound partially by curved faces 26a and 25a, which is adapted to receive the metal part which is to be heated. With this construction it is not necessary to insert the part to be heated through the air space within the transformer core. The ends of the bus-bar which form loop member 25 are held together by a bolt 30, shown in Fig. 9, although a suitable sleeve clamp or other means can be used if desired.

Fig. 10 discloses another embodiment of our invention, similar to the embodiment disclosed in Figs. 8 and 9, in which the secondary winding 25 is of continuous loop or mixtilinear form, similar to that shown in Fig. 7, and has attached thereto members 26 and 31, of the same width as member 25, which have oppositely disposed curved faces 26a and 31a forming opening 27 into which the part to be heated is inserted. Members 26 and 31 are attached to secondary winding 25 by means of bolts 32 or similar suitable holding means. Since member 31 extends through the air space surrounded by core 12, opening 27 is so located that the part being heated need not be inserted into said air space. Members 26 and 31 are made of the same material as member 25, namely, a good electrical conductor such as copper or aluminum bus-bar.

In Fig. 11 we have disclosed a modification of the embodiment of our invention shown in Figs. 8 and 9 in which the secondary winding 25 of substantially mixtilinear form is formed with a plurality of openings 27 adapted to receive several parts to be heated at the same time. In this construction the secondary member 25 has additional members 33, of the same width and material as member 25, connected thereto, said members being suitably bolted by bolts 30 or otherwise attached to member 25 to form the construction shown in Fig. 11. Likewise, the main body of secondary winding 25 has formed thereon a series of protuberances 26 which have curved faces 26a thereon matching the curved faces, 25a and 33a, on the ends of members 25 and 33 to form a series of generally circular openings 27.

Likewise Fig. 12 is a modification of the embodiment of our invention disclosed in Fig. 10 in which a plurality of openings 27 are provided so that several articles can be heated simultaneously. A plurality of members 26 and a plurality of members 31 are matched, curved faces 26a and 31a being opposite each other for each pair, and attached by bolts 32 to form a series of openings 27.

The operation of our invention is as follows:

With the primary winding connected to a suitable source of alternating electric current, such as the standard 60 cycle current, a pulsating magnetic flux will be set up in the magnetic core member of the transformer. As shown in Fig. 13, at a given instant, the primary current I_p will cause the magnetic flux pulsation ϕ in the direction indicated in Fig. 13. This flux pul-

sation will have opposite directions in opposite legs 35b and 35c of the transformer core 35. Consequently in that portion of the mixtilinear secondary loop 36 adjacent leg 35b of the transformer core 35 there will be a voltage induced which will be of opposite polarity to the voltage induced in that portion of the secondary loop 36 adjacent leg 35c of the transformer core 35 with the result that substantially no current flow will take place in the transformer secondary. Secondary 36 thus transforms the magnetic flux pulsations concentrated in core 35 into components of electrical energy which are substantially equal and opposite in direction thus creating a source of energy which is, so to speak, held in leash and which can be aptly described as potential electrical energy. Since the voltages induced in secondary 36 are of opposite polarity we refer to the substantially equal components of potential electrical energy as being of opposite polarity. As the primary current I_p alternates, the magnetic flux ϕ will also alternate but, at each instant, the voltages induced in those portions of the secondary winding 36 adjacent legs 35b and 35c of the transformer core will be of opposite polarity and consequently any secondary current I_s that flows will be due to the unbalanced resistance of the circuit which, for practical purposes, is negligible. However, if a conducting member 37, shown in Fig. 14, is inserted into the secondary circuit 36 between those portions of said circuit adjacent opposite legs 35b and 35c of the transformer core 35, two closed loops, or short-circuited secondary loops, are formed with the result that large amounts of current will flow through the short-circuiting member 37 in both directions, as the current alternates, thereby heating it. Thus member 37 forms a common flow path for the secondary current flowing in each of said closed loops about legs 35b and 35c of core member 35. This is substantially what happens when a metal part, such as a soldering iron head made of copper or other conducting material, is inserted through the openings 16, as shown in Fig. 7 or through the openings 27 shown in Figs. 8 and 10-12. With several metal short-circuiting members inserted in the secondary there will merely be a number of parallel circuits formed and the device will operate even though more than one metal part, such as a soldering iron, is being heated at the same time. The addition of the short-circuiting member 37 thus releases the energy which is normally held in check because of the opposite polarity or bucking direction of the two energy components. Once released the potential energy becomes kinetic and continues to be kinetic as long as the member 37 remains in position. A large portion of the energy is dissipated as heat in the shorting member 37.

The apparatus comprising our invention can be left plugged into the line, i. e., with the primary circuit connected to a suitable source of alternating electric current, without being unduly expensive from an operating standpoint. This is so because our device draws substantial amounts of electric current only when the part to be heated short circuits the secondary member. At other times it acts substantially as if the transformer were open circuited with the consequent result that the only current drawn from the line at these times is the exciting current of the transformer device which forms but a small percent of the total power requirement.

Since the particular article being heated by

our device forms a part of the secondary circuit, electrical current flowing in said secondary circuit will pass through said article and the dissipation of electrical power as heat in said article will be controlled by the magnitude of the electrical current passing through it and the resistance of said article to the current flow. The power loss, as heat, in said article is expressed by the well known Equation I^2R where I is the current flowing in the article, generally expressed in ampere units and R is resistance of the article to current flow, generally expressed in ohms. Since efficient utilization of our heating device demands that the heat be localized in the article being heated, it is desirable that the part being heated, if it is composed of material having substantially the same electrical conductivity as the rest of the secondary circuit, have a higher resistance to current flow per unit area cross-section than the rest of the secondary circuit. Where the materials have substantially the same electrical conductivity, this is accomplished by heating articles which have a smaller cross-sectional area than the remainder of the secondary circuit.

Although optimum results are achieved with the foregoing set-up, the heating of articles of larger cross-section than the remainder of the secondary circuit can be accomplished but, if the materials comprising the secondary circuit have substantially the same electrical conductivity, a longer heating period is required and the heating of the secondary circuit exclusive of the inserted article will be greater. It will be obvious that there is practical limit to the cross-sectional area of the article being heated, depending upon the size of the rest of the secondary circuit and the comparative resistance per unit area of the two, beyond which one cannot go without overheating the rest of the secondary circuit. The permissible range of cross-sectional areas of the part being heated will readily be arrived at by one skilled in the art.

Where the resistance of the part being heated to electric current flow is materially different from that of the remainder of the secondary circuit, heating can nevertheless be accomplished as long as said variance is not so great as to prevent effective current flow in the secondary circuit or, at the other extreme, to prevent the localization of heat in the part being heated due to the extremely low resistance of said part as compared to the rest of the secondary circuit. The permissible variance will be readily apparent to one skilled in the art. Since the secondary loop into which the part to be heated is inserted will be made of material having a high electrical conductivity, such as copper or aluminum, any variation in resistance between the article being heated and the rest of the circuit will generally be caused by the higher resistance of said article. Whether the part being heated is made of the same material as the rest of the circuit is immaterial as long as said part will conduct current and the resistance of said part per unit area compared with the resistance per unit area of the rest of the secondary circuit is within the operable range of values as will be evident to one skilled in the art. Thus, a steel rivet for example could be inserted into a secondary made of copper, and effectively heated. In the usual mode of operation of our device, we insert a copper soldering iron head or a copper solder ladle into a copper bus-bar secondary circuit having a greater cross-sectional area than either the copper

soldering iron head or the copper solder ladle.

It will thus be seen that we have provided a heating device which is particularly suitable for heating soldering irons having a head made of copper or material of like electrical conducting properties, or for heating other small metal parts which are electrically conductive. Furthermore, our device does not utilize an open flame, stands ready for use at any time so long as the primary circuit is plugged in, and develops an intense heat within a relatively short time. The insertion of the part to be heated starts the device into operation and the withdrawal of the heated part causes it to cease operation.

While we have described several particular embodiments of our invention, it is to be understood that we do not wish to be restricted thereto, and that we intend to cover all modifications thereof which would be apparent to one skilled in the art and which come within the spirit and scope of the appended claims.

Having thus described our invention, what we claim as new and wish to secure by Letters Patent is:

1. An electrical heating device comprising a closed magnetic core, a primary winding surrounding a portion of said core, and a closed secondary winding entirely encircling said core, the axis of said secondary winding being substantially at right angles to the axis of said primary winding and lying in the medial plane of the core of said closed magnetic core.

2. An electrical heating device comprising a closed magnetic core, a primary winding surrounding a portion of the periphery of said core, a closed secondary winding entirely encircling said core and symmetrically disposed with respect thereto, the axis of said secondary winding being substantially at right angles to the axis of said primary winding, and lying in the medial plane of the core of said closed magnetic core, and means located in said secondary winding adapted to receive articles to be heated.

3. An electrical heating device comprising a closed magnetic core, a primary winding surrounding a portion of the periphery of said core, and a closed secondary winding entirely encircling said core and symmetrically disposed with respect thereto, the axis of said secondary winding being substantially at right angles to the axis of the primary winding and lying in the medial plane of the core of said closed magnetic core, and said secondary winding having openings therein adapted to receive articles to be heated.

4. An induction heater comprising a closed magnetic core, a primary winding surrounding a portion of the periphery of said core, a closed secondary winding entirely encircling said core and symmetrically disposed with respect thereto, the axis of said secondary winding being substantially at right angles to the axis of the primary winding, said secondary winding being mixtilinear in shape and having openings in each of the long sides thereof, said openings in one side being in alignment with the openings in the other side whereby an article to be heated may be inserted into said aligned openings to form a closed secondary circuit surrounding a portion of the magnetic core.

5. In an induction heater, a secondary winding comprising a closed loop of material having a high electrical conductivity, said secondary winding being mixtilinear in shape and having openings located in each of the long sides thereof,

the openings in one side being in alignment with the openings in the other side, whereby an article to be heated can be inserted in a pair of said openings to form a bridging circuit between the long sides of said mixtilinear secondary.

6. In an induction heater, a closed secondary winding comprising a copper bus-bar of mixtilinear form having openings located in each of the long sides thereof, the openings in one side being in alignment with the openings in the other side, whereby an article to be heated can be inserted in a pair of said openings to form a bridging circuit between the long sides of said mixtilinear secondary.

15. 7. An electrical heating device comprising a closed magnetic core, a primary winding surrounding a portion of the periphery of said core, and a closed secondary winding entirely encircling said core and symmetrically disposed with respect thereto, the axis of said secondary winding being substantially at right angles to the axis of said primary winding and said secondary winding being formed of mixtilinear shape and including a substantially straight conductor portion forming one of the long sides of said secondary, and a plurality of connected curved conductor portions forming the other long side of said secondary.

8. An electrical heating device comprising a closed magnetic core, a primary winding surrounding a portion of the periphery of said core, and a closed secondary winding entirely encircling said core and symmetrically disposed with respect thereto, the axis of said secondary winding being substantially at right angles to the axis of said primary winding and said secondary winding being mixtilinear in shape and including a substantially straight conductor portion forming one of the long sides of said secondary, 35 said straight conductor portion having protuberances attached thereto facing the interior of the secondary, the ends of said protuberances having curved faces formed therein, and a plurality of connected curved conductor portions forming the other long side of said secondary, 40 the ends of said curved portions extending toward the interior of said secondary to a line adjacent the ends of the protuberances attached to the straight conductor portion, and said curved 45 portion ends having curved faces formed therein located opposite the curved faces formed in the ends of the protuberances attached to the straight conductor portion to form a receiving 50 means for articles to be heated.

55. 9. In an induction heater, a closed secondary winding of substantially mixtilinear shape, said secondary being formed from material having a high electrical conductivity, and said secondary including a substantially straight conductor portion forming one of the long sides of said secondary, 60 and a plurality of connected curved conductor portions forming the other long side of said secondary.

10. In an induction heater, a substantially mixtilinear shaped closed secondary winding of material having a high electrical conductivity comprising, a substantially straight conductor portion forming one of the long sides of said secondary, said straight portion having protuberances attached thereto facing the interior 70 of the secondary, the ends of said protuberances having curved faces formed therein, and a plurality of connected curved conducting members forming the other long side of said secondary, 75 the ends of said curved portions extending to-

ward the interior of said secondary to a line adjacent the ends of the protuberances attached to the straight conductor portion, and said curved portion ends having curved faces therein located opposite the curved faces formed in the ends of the protuberances attached to the straight conductor portion to form a receiving means for articles to be heated.

11. An electrical heating device comprising a closed magnetic core, a primary winding surrounding a portion of the periphery of said core, and a closed secondary winding entirely encircling said core and symmetrically disposed with respect thereto, the axis of said secondary winding being substantially at right angles to the axis of the primary winding, and said secondary winding being mixtilinear in shape and including a plurality of protuberances attached to the long sides of said secondary, the protuberances on one side of said secondary winding being in alinement with those on the other side thereof and both sets of protuberances extending toward the interior of the secondary winding to dispose their extremities in adjacent relation.

12. An electrical heating device comprising a closed magnetic core, a primary winding surrounding a portion of the periphery of said core,

and a closed secondary winding entirely encircling said core and symmetrically disposed with respect thereto, the axis of said secondary winding being substantially at right angles to the axis of the primary winding, and said secondary winding being mixtilinear in shape and including a plurality of protuberances attached to the long sides of said secondary, the protuberances on one side being in alinement with the protuberances on the other side and both sets of protuberances extending toward the interior of the secondary so that their ends are adjacent, and curved faces formed in the ends of the protuberances to form a receiving means for articles to be heated.

13. In an induction heater, a closed mixtilinear shaped secondary winding of material having a high electrical conductivity, said secondary having a plurality of protuberances attached to each of the long sides thereof and said protuberances facing the interior of the secondary, the protuberances on one side being in alinement with the protuberances on the other side so that their ends are adjacent, and said ends having curved faces formed therein to form openings adapted to receive articles to be heated.
